(57) **CLAIM**

The ornamental design for a hat box, as shown and described.

DESCRIPTION

FIG. 1 is a front, top perspective view of a hat box, showing my new design;

FIG. 2 is a rear, bottom perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top plan view thereof;

FIG. 7 is a bottom plan view thereof;

FIG. 8 is a front, top perspective view of the hat box in an opened state; and,

FIG. 9 is a bottom plan view of the hat box in an opened state.

The dashed broken lines in the figures are for the purposes of illustrating portions of the hat box that form no part of the claimed design.

1 Claim, 9 Drawing Sheets
